Primary Examiner—Holly Baynham

[57] CLAIM

The ornamental design for a three point utility trailer, as
shown.

DESCRIPTION

FIG. 1 is a right perspective view of a three point hitch off
road trailer showing my new design;

FIG. 2 is a top plan view thereof;

FIG. 3 is a elevation view of one side, the opposite side
being a mirror image thereof;

FIG. 4 is a front elevational view thereof; and,

FIG. 5 is a rear elevational view thereof.
